UNITED STATES PATENT OFFICE.

ANDREW R. HUMES, OF KNOXVILLE, TENNESSEE.

CARPENTER'S WORK-BENCH.

No. 918,155.

Specification of Letters Patent. Patented April 13, 1909.

Application filed August 26, 1908. Serial No. 450,384.

To all whom it may concern:

Be it known that I, ANDREW R. HUMES, a citizen of the United States, residing at Knoxville, in the county of Knox and State 5 of Tennessee, have invented a new and useful Improvement in Carpenters' Work-Benches, of which the following is a specification, reference being had to the accompanying drawing.

My improvement relates particularly to carpenters' work benches in which provision is made for securing boards and other pieces of wood for planing or other dressing.

The object of the invention is to provide 5 a work bench embodying simple and efficient mechanism for quickly and firmly securing to the top of the bench boards and other pieces of wood of varying lengths.

In the accompanying drawing, Figure 1 is a plan of a work bench embodying my improvement, portions being broken away; Fig. 2 is a side elevation of the same bench, portions being broken away; Fig. 3 is an upright section on the line 3—3 of Fig. 1, looking toward the right; Fig. 4 is a perspective view of the movable clamp member.

Referring to said drawings, 1, 1 are the usual standards of the bench; 2, 2 are longitudinal, upright boards or aprons secured to the outer sides of said standards and extending to the top, 3. Adjacent the left hand front corner of the top is a stop or dog, 4, which may be movable or immovable. If immovable, it must be adapted to be rendered temporarily immovable. In the top, a little way rearward of said stop are a row of upright sockets, 5, such row extending lengthwise of the bench from near said stop toward the right as far as may be desired, preferably nearly to the right hand end of the top. A thin, flat movable member, 6, is to be secured in any one of said sockets. Said clamp member has a downward directed stud, 7, adapted to fit into any one of said sockets and constitute a journal for the turning of said clamp member flatwise upon the upper face of the bench top. Normally said clamp member stands approximately crosswise of the length of the table, one end of said member extending as far forward as does the stop or dog, 4. To the opposite end of said clamp member is secured a cord or chain, 10. Said cord may be secured in a variety of ways. The drawings show a band, 8, surrounding said member and having an eye, 9, through which

said cord extends. Near the right hand end of the bench top, said top has an opening, 11, in which is seated an idle guide pulley, 12. Said cord extends around said pulley 60 and thence to a shaft, 13, which extends transversely and horizontally across the bench below the top, 3, and rests in bearings, 14, in the side boards, 2, said cord being secured to said shaft so as to adapt the latter 65 for winding the cord upon the shaft when the latter is rotated in the proper direction. On said shaft is a head, 15, bearing a cross-arm, 16, to be engaged by the hand for the rotation of said shaft. Between the head, 70 15, and the adjacent side board, 2, is a ratchet wheel, 17, rigidly surrounding said shaft; and a pawl, 18, is hinged at 19 to the side board, 2, in proper relation to engage the teeth of said ratchet wheel. 75

In operation, the piece of wood which is to be planed or dressed is placed in front of the stop or dog, 4, and the movable clamp member, 6, is then placed near the opposite end or edge of said piece of wood and approximately cross-wise of the table, the stud, 7, being pressed into the nearest socket, 5. Then the shaft, 13, is turned for the tightening of the cord, 10, whereby the rear end of the movable clamp member is drawn toward the right, said member turning bodily with said socket for a bearing, and the forward end of said movable clamp member turning toward the left and bearing against said piece of wood. In practice it has been 90 found that by this means the piece of wood may be so firmly clamped that it may be planed toward the movable clamp member as well as toward the fixed stop, 4. And it will be observed that this mechanism 95 may be used for holding or clamping pieces or work while being fitted or nailed or screwed or glued to each other. In other words, the mechanism partakes of the nature of a clamp. 100

I claim as my invention:

1. In a work bench, a top having in its upper face a row of upright sockets, said row being parallel to the length of the bench, a stop, a flat, one-piece, movable 105 clamp member adapted to rest directly upon the upper face of the bench top and having a stud adapted to enter said sockets, and means for turning said clamp member in a horizontal plane, said stud turning as an 110 upright journal in the socket in which it rests.

2. In a work bench, a top having in its upper face a row of upright sockets, said row being parallel to the length of the bench, a stop, a flat, one-piece, movable clamp member adapted to rest directly upon the upper face of the bench top and having a stud between its ends adapted to enter said sockets, and means for turning said clamp member in a horizontal plane, said 10 stud turning as an upright journal in the socket in which it rests.
3. In a work bench, a top having a row of sockets, said row being parallel to the front of the bench, a stop, a movable clamp member having a stud adapted to enter said 15 sockets, a cord for turning said clamp member, and mechanism for winding said cord.
4. In a work bench, a top having a row of sockets, said row being parallel to the length 20 of the bench, a stop, a movable clamp member having a stud between its ends adapted to enter said sockets, a cord for turning said clamp member, and mechanism for winding said cord.
5. In a work bench, a top having a row of 25 sockets, said row being parallel to the front of the bench, a stop, a movable clamp member having a stud adapted to enter said sockets, a cord for turning said clamp member, mechanism for winding said cord, and mechanism for locking said winding mechanism.
6. In a work bench, a top having a row of 30 sockets, said row being parallel to the length of the bench, a stop, a movable clamp member having a stud between its ends adapted to enter said 35 sockets, a cord for turning said clamp member, mechanism for winding said cord, and ratchet mechanism for locking said winding mechanism.
- 40 7. In a work bench, a top having a row of sockets, said row being parallel to the front of the bench, a stop, a movable clamp member having a stud adapted to enter said
- sockets, a guide pulley, a cord secured to 4 said clamp member and extending over said pulley, and mechanism for winding said cord.
8. In a work bench, a top having a row of 5 sockets, said row being parallel to the length of the bench, a stop, side boards below said top, a shaft journaled in said side boards, a movable clamp member having a stud adapted to enter said sockets, and a cord extending from said clamp member to said shaft.
9. In a work bench, a top having a row of 6 sockets, said row being parallel to the length of the bench, a stop, side boards below said top, a shaft journaled in said side boards, a guide pulley, a movable clamp member 6 having a stud adapted to enter said sockets, and a cord extending from said clamp member to said shaft.
10. In a work bench, a top having a row 7 of sockets, said row being parallel to the length of the bench, a stop, side boards below said top, a shaft journaled in said side boards, a movable clamp member having a stud adapted to enter said sockets, a cord extending from said clamp member to said shaft, and mechanism for locking said shaft.
11. In a work bench, a top having a row 8 of sockets, said row being parallel to the length of the bench, a stop, side boards below said top, a shaft journaled in said side boards, a guide pulley, a movable clamp member having a stud adapted to enter said sockets, a cord extending from said clamp member to said shaft, and mechanism for locking said shaft.
- In testimony whereof I have signed my name, in presence of two witnesses, this the 24th day of August, in the year one thousand nine hundred and eight.
- ANDREW R. HUMES.
